Term of patent 14 years

(Cl. D33—7)

FIG. 1

FIG. 2

Fig. 1 is a front perspective view of a desk embodying our new design, and

Fig. 2 is a view of the opposite side of the side shown in Fig. 1.

The upper portion of the back of the desk is substantially like that shown in Fig. 2 except that said back portion is elongated to a length corresponding to the length of the upper front portion of the desk as shown in Fig. 1.

The top of the desk is subdivided into a plurality of substantially uniform squares.

We claim:

The ornamental design for a desk, substantially as shown and described.
